UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

SEWING-MACHINE.

1,299,625.

Specification of Letters Patent.

Patented Apr. 8, 1919.

Application filed December 28, 1914. Serial No. 879,484.

To all whom it may concern:

Be it known that I, DUDLEY S. SEYMOUR, a citizen of the United States, residing at Oak Park, in the county of Cook, State of Illinois, have invented certain new and useful Improvements in Sewing-Machines, of which the following is a description, reference being had to the accompanying drawings and to the figures of reference marked thereon.

The invention relates to new and useful improvements in sewing machines, and more particularly to the mechanism for operating the needle, the feed and the looper of a machine having a work-supporting arm.

An object of the invention is to provide a machine of the above character wherein the feeding mechanism feeds the material lengthwise of the arm, with a main shaft which extends at right angles to the longitudinal axis of the arm, and devices actuated by said main shaft for reciprocating the needle and operating the looper and the feed.

A further object of the invention is to provide a machine of the above character with an upper shaft which extends lengthwise of the overhanging arm and is connected to the needle bar for reciprocating the same.

These and other objects will in part be obvious, and will in part be hereinafter more fully disclosed.

In the drawings which show by way of illustration one embodiment of the invention,

Figure 1 is a view in side elevation with parts broken away to show the inner mechanism of a machine embodying my improvements;

Fig. 2 is a top plan view of the same, with parts broken away and in section to show the upper shaft and the connections thereto;

Fig. 3 is an enlarged rear end view with parts broken away and in section to show the mechanism for operating the various parts from the main shaft;

Fig. 4 is a front end view with the face plate removed, so as to show the connection between the upper shaft and the needle bar;

Fig. 5 is a detail in side elevation, showing a portion of the connection between the main shaft and the upper shaft which reciprocates the needle bar;

Fig. 6 is a sectional view on the line 6—6 of Fig. 5.

The invention consists generally in providing a machine which has a standard from which projects a work-supporting arm and an overhanging arm, at the forward end of which reciprocates the needle bar. The feed dog is disposed so as to feed the material lengthwise of the work-supporting arm. A looper located in the arm cooperates with said needle.

The needle bar is reciprocated by an upper shaft which is mounted in suitable bearings in the overhanging arm and is oscillated from the main shaft which extends crosswise of the standard and at right angles to the axis of the work-supporting arm. The looper is carried by a shaft which extends lengthwise of the arm, and this shaft is oscillated and moved endwise by suitable actuating devices operated by the main shaft.

Referring more in detail to the drawings, my improved machine consists of a bed 1, from which rises a standard 2. The standard 2 carries a forwardly projecting work-supporting arm 3, which is preferably cylindrical in shape. The standard 2 also carries an overhanging arm 4, having a needle head 5, at the forward end thereof, in which reciprocates a needle bar 6. The needle bar 6 carries, as herein shown, two needles 7 and 8.

Cooperating with the needles within the work-supporting arm 3 is a looper 9, which is fixed to a looper shaft 10 mounted in suitable bearings 11, 11, carried by said work-supporting arm. This looper-supporting shaft 10 extends into the standard at the rear end thereof. The main shaft 12 extends crosswise of the standard 2; that is, at right angles to the longitudinal axis of the work-supporting arm 3. This cross shaft 12 is provided with a suitable eccentric, with which cooperates an eccentric strap carrying a link 13, connected at its lower end to a rock shaft 14.

At the rear end of the looper shaft 10, there is an arm 15. This arm 15 carries a ball stud, to which is connected a link 16. The other end of the link 16 is connected to the rock shaft 14. As the main shaft 12 rotates, the rock shaft 14 will be oscillated, and this in turn will oscillate the looper shaft 10. The link 16 moves from a position substantially in line with the arm of the rock shaft to which it is connected, to a posi-

tion shown in Fig. 3. When these parts are in line, the looper is at the forward end of its stroke, and is given a dwell. This particular looper-operating mechanism forms no part of my present invention.

Also mounted on the main shaft 12 is a second eccentric, with which co-operates an eccentric strap carrying a link 17. The link 17 at its lower end is connected to an arm 18, fixed to a cross shaft 19. The cross shaft 19 carries a second arm 20. The looper shaft is moved endwise for giving the looper its needle avoiding movement through a connection with this arm 20. Mounted freely on the looper shaft 10 between spaced collars 23^a and 23^b, which are fixed to the shaft, is a sleeve 23. This sleeve 23 has a depending arm or bracket 22. A link 21 is pivotally connected at one end to this arm or bracket 22, and at its other end to the arm 20. On the work supporting arm 3 is a fin 3^a which engages the groove in the arm or bracket 22. This prevents the arm or bracket 22 from oscillating with the shaft 10 and at the same time permits the sleeve to be moved endwise through the link 21 as the arm 20 vibrates.

The material being sewed is fed up the arm by a feed dog 24, mounted on a feed bar 25. The feed bar 25 at its rear end is slotted to engage a pin 26. The rear end of the feed dog moves back and forth on this pin, and such pin may oscillate to permit the front end of the feed bar to be raised and lowered.

Mounted on the looper shaft 10 is an eccentric, which engages a bracket 27 carrying the feed bar 25. As the looper support oscillates, this eccentric will raise and lower the feed bar, which in turn will raise and lower the feed dog. The cross shaft 19 carries a third arm 28, which is slotted, and a link 29 connected to said slotted arm at one end is also connected at its other end to the feed bar 25. As the arm 28 oscillates, the feed bar 25 will be moved back and forth.

The needle bar 6 is provided with a collar 30, which carries a projecting lug to which is attached a link 31. Mounted in suitable bearings 31^a in the overhanging arm, is a shaft 32. This shaft 32 carries an arm 33, to which the upper end of the link 31 is pivotally connected. The arm 33, as clearly shown in Fig. 2 of the drawings, is carried by a collar 34 fixed to the shaft 32. A counterbalancing weight 35 is fixed to the forward end of the shaft by a set screw 36. This counterbalancing weight 35 is located substantially opposite the arm 33, and is connected to the needle bar 6, so that the weight 35 counterbalances the weight of the arm 33, the link 31, the needle bar and the parts carried thereby.

The shaft 32 extends through the bearing 31^a at the rear end of the machine and carries an arm 37, clamped to the shaft by

suitable screws 38. The main shaft 12 is provided with a crank 39 carrying a ball 40. The crank 39 is between the eccentrics on the shaft 12. A link 41 co-operates with this ball 40 at one end, and at its upper end is connected to a ball stud 42 on the outer end of the arm 37. As the main shaft 12 rotates, this crank 39 will through the link 41 oscillate the arm 37 and in turn oscillate the shaft 32, which reciprocates the needle bar 6. Inasmuch as the main shaft extends at right angles to the shaft 32, the link 41 must have a universal connection with the crank 39, and this is accomplished by the ball 40 above described. This connection between the link 41 and the crank would permit the link, however, to wobble on its connections as the shaft rotates. In order to prevent this wobbling of the link, and thus prevent unnecessary noise, I have provided said link adjacent its upper end with an outwardly projecting arm 43. This arm 43 carries a ball stud at its outer end, with which is connected a link 44. The link 44 at its inner end is freely journaled on a ball stud 45 carried at the end of the shaft 32 and concentric with the axis of the shaft. This link 44 moves up and down with the oscillations of the shaft 32, and serves solely to prevent the wobbling of the link 41 on its connections. The main shaft 12 is driven by a suitable belt wheel 46, having the hand wheel 47 attached thereto.

In this type of machine, the operator in feeding the material sits at the end of the work supporting arm. The hand wheel 47 is readily accessible to the operator, so the main shaft 12 may be turned by hand to position the needle for the placing of the material in the machine, for the removing of the material from the machine or for threading the needles. The material is held on the work-supporting arm by a presser foot 58, carried by a presser bar 49. The presser bar may be raised by a hand lever 50, connected to a link 51. The link 51 is connected eccentrically relative to the pivot of the hand lever 50, and has a slotted connection with the bracket 52 at the upper end of the presser bar 49. This pressure bar may also be raised by a treadle, if desired.

From the above description it will be apparent that I have provided a sewing machine wherein the material may be fed lengthwise of a supporting arm, and wherein the needle bar is oscillated from a positively oscillated shaft extending lengthwise of the overhanging arm, and this shaft in turn is positively actuated by a cross shaft which is journaled in the standard and extends at right angles to said needle shaft, and also at right angles to the work-supporting arm, which positions the hand wheel of the main shaft so it may be readily accessible to the operator.

It will further be seen that I have pro-

vided means for positively reciprocating the feed dogs from this main shaft, and also for positively actuating the looper from said shaft.

5 It is obvious that minor changes in the construction and arrangement of the parts may be made, without departing from the spirit of my invention as set forth in the appended claims.

10 Having thus described my invention, what I claim as new and desire to secure by Letters Patent, is:—

15 1. A sewing machine including in combination a standard, a work support, an overhanging arm, a main shaft in said standard extending at right angles to the longitudinal axis of said arm, a shaft in said overhanging arm, a link operated by the main shaft and connected to the shaft in the overhanging arm for oscillating the same, an arm projecting laterally from said link at the upper end thereof, a second link connected to said arm at one end and at the other end to a ball stud mounted on the 25 shaft in the overhanging arm and concentric with the axis thereof, a needle bar, a needle carried thereby, and devices for reciprocating the needle bar from said shaft in the overhanging arm.

30 2. A sewing machine including in combination, a standard, a work-supporting arm projecting from said standard, an overhanging arm, a main shaft in said standard extending at right angles to the longitudinal axis of said work-supporting arm, a feed dog for feeding the material lengthwise of said work-supporting arm, means for actuating said feed dog from said main shaft, a shaft in said overhanging arm, 35 a needle bar, needles carried thereby, means for reciprocating said needle bar from said shaft, an arm projecting from said shaft, a crank arm formed in said main shaft, a link operated by said crank arm and attached to the arm on the shaft in the overhanging arm for oscillating the same, said link having a universal connection with the crank in the main shaft and also with the arm on the oscillating shaft, an arm projecting laterally from said link at the upper 45 end thereof, a link connected to said arm at one end and at the other end to a ball stud mounted on the shaft in the overhanging arm and concentric with the axis thereof.

50 3. A sewing machine including in combination, a standard, a work-supporting arm projecting from said standard, an overhanging arm, a main shaft in said standard extending at right angles to the longitudinal axis of said work-supporting arm, a feed 55 dog for feeding the material lengthwise of

said work-supporting arm, means for actuating said feed dog from said main shaft, a shaft mounted in said overhanging arm, an arm mounted adjacent the forward end 65 of said shaft and projecting laterally therefrom, a needle bar, needles carried thereby, a link for connecting the arm on the shaft with the needle bar, a weight mounted on the forward end of said shaft at the opposite 70 end of its axis from said arm, a second arm at the rear end of said shaft, a link connected to said second arm, an eccentrically disposed member carried by said main shaft with which said link coöperates for oscillating the shaft in the overhanging arm, an arm projecting laterally from said link at the upper end thereof, and a second link connected to said arm at one end and to a ball stud mounted on the shaft in the over- 80 hanging arm at its other end.

4. A sewing machine including in combination, a standard, a work support, an overhanging arm, a main shaft in the standard extending at right angles to the longitudinal axis of said arm, a shaft in said overhanging arm extending longitudinally thereof, means for actuating said shaft from said cross shaft in the standard, a needle bar, means for reciprocating said needle bar 90 from the said shaft in the overhanging arm, a needle carried by the said needle bar, a looper shaft in said work support, a looper operated thereby, and means located in the standard for oscillating the looper shaft and 95 for moving the same endwise.

5. A sewing machine including in combination, a standard, a work supporting arm carried by said standard, an overhanging arm carried by said standard, a shaft 100 in said overhanging arm extending longitudinally thereof, a needle actuated by said shaft, a shaft in said work supporting arm, a looper mounted on said shaft, a main shaft 105 in said standard extending at right angles to the axis of said overhanging arm, an eccentric on said main shaft, devices between said eccentric and said looper supporting shaft for oscillating the same, a second eccentric on said main shaft, devices between 110 said second eccentric and said looper supporting shaft for moving the same endwise, a crank located between said eccentrics, and means actuated by said crank for oscillating the shaft in the overhanging arm.

In testimony whereof I affix my signature in the presence of two witnesses.

DUDLEY S. SEYMOUR.
